DENTAL ILLUMINATOR

Donald E. Everburg, Southbridge, and Richard R. Maiese, Webster, Mass., assignors to American Optical Corporation, Southbridge, Mass.

Filed Dec. 19, 1969, Ser. No. 20,576

Term of patent 7 years

Int. Cl. D26—02

U.S. Cl. D48—20

FIG. 1

FIG. 2

FIG. 3

FIG. 4

FIG. 1 is a perspective view of a dental illuminator showing our new design.

FIG. 2 is an elevational view of one side of the dental illuminator, the opposite side thereof being of substantially the same appearance;

FIG. 3 is a front elevational view thereof; and

FIG. 4 is a top plan view thereof.

We claim:

The ornamental design for a dental illuminator, as shown and described.
